SANITARY PRESERVING CAN OR CONTAINER

Filed March 12, 1927

UNITED STATES PATENT OFFICE

HEINRICH KARL, OF JERSEY CITY, NEW JERSEY

SANITARY PRESERVING CAN OR CONTAINER

Application filed March 12, 1927. Serial No. 174,917.

This invention relates to a new method for closing the can, etc., hermetically and for opening it only on the top without tearing up the sheet metal of which said top part is made, whereby it is prevented that metal particles fall into the eatables contained in the can, etc., and so prevent injuries to the intestinal organs of the consumer and therefore prevent severe diseases 10 that may develop after said injuries.

In this invention there are two modifications shown and described, one of which is characterized by having a cover for the can opening that is to be taken off entirely when 15 the can is to be opened, which in this respect belongs to the kind already known in the art, while in the other modification which is new in the art the part that covers the opening must be bent for uncovering the opening of 20 the container such as a can, etc.

Both modifications have certain new and common characteristics in their construction that serve for preventing particles from binding materials that will be broken at the 25 opening of the can, etc., from falling into the contents of the container and which serve also for permitting the sweeping off of such particles or dust, etc., when the can has been already opened whereby however these 30 particles, etc., will not fall into the contents of the container.

More particularly the invention consists partly of the method of forming the top of the can, etc., either of two or more sections 35 according to the shape or contents of the can (or box), etc., and the number of openings therein, and if the top consists of more than two sections these sections are then united with a binder at a certain cutting line of 40 two (or more) of the sections and if the top part is made of only two sections the binder serves for uniting the section that covers the opening with the section that leaves the opening. Another characteristic 45 of the invention is to bend up or roll up or fold up that edge of said last mentioned section that surrounds wholly or partly the opening or openings of the can and in such manner that the bent or folded part forms 50 the highest point of the container when the

section is taken away that covers the opening. Still another characteristic of the invention although already known in the art is the employment of a wire or cord or fibre, etc., that is to be laid along the visible cutting line of that section that covers the opening, to which wire, etc., will be applied afterward to said binder in a manner that it covers said wire, etc., partly and this wire, etc., serves for breaking said binder when the can 55 is to be opened. 60

Another characteristic common to both modifications is to shape the uppermost section that forms the cover for the opening of the container much larger than the opening, so that the sealing line is very much further distanced from the border of the opening than it is designed in those containers that are known in the art, and this is made for the purpose of preventing particles 65 of the binder from falling into the contents 70 of the container at the opening thereof.

A preferable embodiment of the invention is illustrated by the accompanying drawings, in which like reference characters 75 indicate like parts, and of which—

Figure 1 is a sectional view of part of the can and part of the top thereof;

Figure 2 is a sectional view of a part of another can and also of a part of the top 80 thereof, which represents a slight modification of that shown in Figure 1 and supposed to be made wholly of sheet metal;

Figure 3 is a top view of the container or can, which top part is made of two sections 85 which are so joined that the string or wire, etc., must be laid in two right angles;

Figure 4 shows in elevation the can whose top is shown in Figure 3;

Figure 5 is a top view of the container with 90 a large and a small opening; the top part is therefore made of three sections of which those that cover the openings are cut out in curves that form the lines on which both sections are joined to the third, and the wire 95 etc. must then be laid also in the curved line of these sections;

Figure 6 is a top view of the container whose top part is made of two sections of which the one that covers the opening is cut 100

out in a manner that the string or wire etc. must be laid in a right angle;

Figure 7 is a top view of the container cover that is made of two sections of which the one that covers the opening is cut out as a complete circle, hence also the wire or cord etc. must be laid accordingly in a circular way;

Figure 8 is a top view of a box of rectangular form that may serve for packing sardines etc., the top part therefor being made of two sections of which the one forming the opening is made of one piece with those of the side of the box, the string etc. therefore must be laid accordingly into a position that forms two right angles; and

Figure 9 shows in a perspective view the can body of Figure 8, which can may be filled with sardines and having the cover removed.

According to the object of the invention the top part *a* or *b* or *b'* or *c* must be so constructed that no metal particles nor other substances can fall into the contents when the can etc. is being opened. For preventing also the falling of particles of the binder into the contents of the can etc. one of the sections of the top part, which I will term the section or piece that leaves or forms the opening or openings, must have the bent up or rolled up edge 10 of Figure 1, or 11 of Figure 2, respectively. If the cover is made of a single piece, as illustrated in Figure 8, then it must be the edge around the opening of the box or can etc. (that corresponds more or less with the edge of the section that covers that opening) that must be bent upward or rolled up or folded as exemplified in Figure 9, and indicated by the reference numeral 12. This bent up or rolled or folded part 10, 11 or 12 forms a barrier that prevents the falling of particles of the binder 13 into the contents of the can when the sections that cover the openings, namely, the upper section 14 of Figure 1, or 15 of Figure 2, or the cover *c* shown in Figure 8, are being removed from the container or bent up when the wire or string 16 is pulled away, as will be more plainly explained afterward. Preferably, the top part is to be put on the can or container etc. in the non-sealed condition, that is, the section that forms the opening or openings and in certain cases also the sections that cover the openings (see, for instance, Figures 1, 2, 3, 4, 5 and 6), must be fastened to the can body in the manner as shown in Figures 1 or 2, respectively. If the container is made of glass, porcelain, or earthenware and not of sheet metal, then a method must be chosen as shown in Figure 1, which is also subject of my patent application, Serial No. 165,611, filed February 3, 1927. But if the can body is made of sheet metal the outer edge-parts of the top portion may be folded up with the upper edge-part of the can body as illus-

trated in Figure 2, which method is usually employed in preserving cans.

Referring more particularly to Figures 1, 2, 3, 4, 5, 6 and 7, the section 18 is the section in which the opening or openings are left and to which section the characters *a*, *b*, *c*, etc. are added according to the shape thereof. The borders are so cut that some thereof serve for being fastened to the can. These borders are indicated by 20 in Figure 1 and for the other figures the characters *a* or *b* or *c*, etc. are added for making the distinction. This part 20, 20*a*, 20*b*, etc. first is to be bent downward to form a right angle, as shown at 21 in Figure 1 or 21*a* in Figure 2, and when the can etc. is to be closed hermetically it must be bent again either in the manner shown in Figure 1 or in Figure 2 as the shape of the can etc. necessitates it or according to the material of which the can is made. If the can 22 is made of glass or earthenware, then the method must be employed as shown in Figure 1, where a string 23 or wire etc. coated with a binder 24 such as wax, tar, rosin, etc. or a soft solder, is laid between said part of the border and the can, preferably underneath a somewhat outwardly projecting part 25 thereof. The lower part of the portion 20 will then be pressed against said outwardly projecting part 25 thereby squashing the still soft binder whereby the can will be hermetically closed at that part. If the can is made of sheet metal then the border 20 simply needs to be folded up with the border part of the can as shown in Figure 2 in which the can is indicated by 22*a* and the part of the section 18*a* that is to be folded therewith is indicated by 20*a*.

Now we will assume that the cover is made only of two sections, although in some cases three sections would be more practical, (see, for instance, the can of Figure 5 where there are two openings provided for, of which one is small and the other large, and that are covered by the sections 14*b*, 14*b'*, respectively; the small opening may serve for pouring out the contents only in small quantities, while the large one may serve for emptying the can at once). The section 18, 18*a*, etc. then must have another border that wholly or partly surrounds the opening of the can. This border is indicated by 10 in Figure 1 and by 11 in Figure 2. According to the dimension which the opening shall possess the border 10 or 11 may have any of the most practical shapes and in Figures 3, 5, 6 and 7 some are indicated by dotted lines. This border or its edge is preferably bent up, as shown in Figure 1, but it may be rolled up, etc., as shown in Figure 2 and has to form the highest part of the section 18, 18*a*, 18*b*, 18*c*, 18*d*, 18*e* and 29. This part 10 may be bent up as high as one eighth of an inch at the point that is farthest from the upper edge of the can 22, 22*a* etc., but it can be much

lower at the point where it meets with that edge of the can. In Figure 3 the highly bent-up part is indicated by 10' while the little bent-up parts are indicated by 10''. The purpose of making the bent-up edge lower at the part 10'' is to facilitate the fastening of this section 18, 18a etc. to the can and also to facilitate the fastening of the other section 14, 15 to the can. This section 14, 15 serves for covering the opening left open by the section 18, 18a etc. and is to receive a shape that exceeds somewhat that of the opening. If desired the shape of this section 14, 15 etc. can be far in excess of that of the opening. Such an example is shown in Figure 2 where the section 15 extends as far beyond the rolled up border 11 that it nearly covers the whole top of the can. This is simply for the purpose to prevent particles of the binder to come too near to the edge of the opening when the can is being opened, and by lifting somewhat the section 15, as shown by the dotted lines, all such particles can be swept off before this section is entirely taken off the can. As shown in Figure 4, the section 14a, that may be identical with the section 14 of Figure 1 or 15 of Figure 2, is similarly fastened to the can 22b as is the section 18b and the method of fastening may be that shown in Figure 1 or Figure 2, or any other suitable method may be employed. The edge-part 26 or 27 that lays upon the section 18, 18a etc. is bent down or slanted and preferably should touch the upper surface of that section 18. The wire or string 16 etc. is to be laid very tightly against the edge 26 or 27 and corresponding surface of the section 18, 18a etc. and the binder 13 then must be applied so that it covers that wire or string 16 etc., and at the same time binds parts of the section 14 or 15 with the section 18, 18a etc. The wire or string extends over the edge where the sections are fastened to the can and the consumer simply needs to grip that portion of wire or string and pull therewith the whole wire 16 away from the border 26, 27 when he wants to open the can. The binder 13 breaks thereby and the section 14 or 15 can be lifted with the fingers or with some tool, as a knife etc., whereby the metal sheet of that section will be bent (but not broken) at a certain line that corresponds with the points on which the border 26 or 27 reaches the upper edge of the can and this bending line is shown by a dotted line in Figures 3, 5 and 6 and is indicated by the reference numeral 28b, 28c and 28d, respectively. Also the cover c on the box shown in Figure 8 must be bent when the box is to be opened and in this case the bending line corresponds with the left-side edge of the box. If the sections 14a, 14b and 14c are fastened to the can in a manner as the section 18 of Figure 1 is fastened thereto, then it will be possible to take these sections entirely off. In the

modification of Figure 7 in which only the section 18e is fastened to the can 22, the section 15a can be taken off entirely if the wire or string 16 is pulled away and therethrough the binder 13 broken. If the can 22 of Figure 7 is made of sheet metal and not of glass, earthenware etc., it will not be necessary to make a special section 18e since this part may then be formed in one piece by the can part 22. A somewhat similar proposition is made in the modification shown in Figures 8 and 9 where the upper edge of the can body 22f is bent so that it makes a horizontal surface 29 that surrounds the opening 30 and the edge 12 of this surface is bent up (see Figure 9).

Having described herewith a practical and simple method of safeguarding the people that use canned foods from deadly diseases, I wish to express my view that minor changes are possible in this invention without departing from the spirit and scope thereof.

What is claimed is:

1. In a preserving container having a bottom and side walls, a top for said container having an air opening therein, a cover for said opening, one portion of the cover being seamed to the side walls, the remaining portion of the cover extending beyond the opening and being secured to the top at a substantial distance from said opening by means of binding material whereby, when the binding material is broken, parts thereof will not fall into the opening.

2. In a preserving container having a bottom and side walls, a top for said container having an air opening therein and a bent edge bordering said opening, a cover for said opening extending beyond the opening and being secured to the top by means of binding material at such distance from said bent edge that a space is left between said bent edge and the edge of the cover, said space left empty and being spaced horizontally considerably over its height, and being of such proportion that, when the container is being opened and therefore the binding material broken, parts thereof or metal particles will not fall into the opening.

Respectfully submitted.

HEINRICH KARL.
